The ornamental design for headwear, as shown and described.

DESCRIPTION

FIG. 1 is a top, front, right perspective view of headwear embodying my our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a top, front, right perspective view of the headwear of FIG. 1 with the neck cape shown not deployed;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top plan view thereof; and,

FIG. 14 is a bottom plan view thereof.

The broken line representations in the figures show unclaimed environmental features. Thus, the broken lines are not part of the claimed design.

The nature of this product pertains to headwear, such as a hat or cap having a deployable neck cape.
